DESIGN FOR A LANTERN

Will H. Smith, Warsaw, N. Y., assignor to Embury Manufacturing Company, Warsaw, N. Y., a corporation of New York

Application May 3, 1937, Serial No. 69,122

Term of patent 14 years

To all whom it may concern:

Be it known that I, Will H. Smith, a citizen of the United States, residing at Warsaw, in the county of Wyoming and State of New York, have invented a new, original, and ornamental Design for a Lantern, of which the following is a specification, reference being had to the accompanying drawing, forming part thereof.

Fig. 1 is an elevational view of the lantern

viewed from one direction, showing my new design, and

Fig. 2 is a similar view of the lantern when viewed at about 45° from the direction of view in Fig. 1.

I claim:

The ornamental design for a lantern, substantially as shown.

WILL H. SMITH.
